PROCESS AND MEANS FOR BURNING
CEMENT SLURRY

Adolphe Busch, Antwerp, Belgium

Application November 25, 1932, Serial No. 644,396
In Belgium December 11, 1931

9 Claims. (Cl. 222—7)

This invention relates to the spreading and apportionment of matter to be dried or calcined introduced in the form of jets of slurry, in the opposite direction to the currents of hot gases in rotary kilns such as those employed for the wet process manufacture of cement.

To obtain efficiency in these kilns it is important that the slurry be spread in a finely divided state throughout the drying area of the kiln, in order to ensure intimate contact between the particles of slurry and the hot gases serving to dehydrate them. These conditions are partly obtained by injecting the slurry directly on to chains or other analogous members suspended within the kiln for the purpose of increasing the heating surface, and which break up and spread the jet of slurry by checking its trajectory during rotation of the kiln. However, these chains can only be arranged in somewhat reduced number and at a certain distance from the entrance of the kiln if it is desired to keep the slurry from bouncing out of the furnace when striking the first set of chains and, for this reason an important portion of the drying zone is not effective. Again, at the moment of impact the chains tend to yield and thereby affect the extent of the dispersion of the jets of slurry, which remain more or less compact.

One of the advantages of the present invention is that it enables the entire length of the drying zone to be utilized effectively, and when chains are used it also enables this length to be reduced by increasing the number of chains which can be used. A further advantage is gained by the absence of any yielding of the chains against which the slurry now impinges with less force than heretofore.

According to the process according to my invention, matter such as slurry is injected in one or more jets on to one or more series of rigid deflectors located within the kiln in such manner as to be presented in succession to said jet or jets which jets are wholly broken up by impact therewith, the particles of slurry rebounding therefrom at a relatively slow speed through the heating gases.

These deflectors may be employed in conjunction with or without chains as desired, and if said deflectors are appropriately inclined, it is possible to control the rebound of the slurry in such manner that when chains are employed, those chains located immediately at the entrance of the kiln are sprinkled indirectly without the slurry rebounding from the kiln. In addition, as it is no longer necessary to maintain spaces

between the chains for the passage of the jet or jets of slurry, the number of chains in proportion to the deflectors can be considerably increased, and as a result the length of the kiln can be reduced without diminishing its output.

An important feature of the invention is the arrangement of the deflectors so that the slurry will be automatically apportioned throughout the length of the drying zone in a quantity definitely proportional to the temperature of the heating gases at different points in the length of the said drying zone, thus ensuring the best employment of the heat from said gases and simultaneously drying the slurry to the same degree throughout the length of the kiln. This result is obtained by disposing the deflectors in helicoidal rows and by forming them, from the point of entry of the slurry into the kiln, either of a width which progressively increases, or else with a spacing which gradually decreases, whereby during rotation of the kiln, those deflectors which are situated in the hottest part of the drying zone remain in the trajectory of the jet of slurry for a longer time than those in the cooler portion, and receive and spread on the adjacent chains a greater quantity of slurry. In addition, it is advantageous to offset or stagger the deflectors of one row with respect to those of the adjacent row or rows.

Whatever may be the arrangement of the deflectors, it follows that the violent impact of the jet of slurry thereon tends not only to scatter the slurry in drying particles, but also to expel a considerable quantity of the water contained therein so that the drying action of the hot gases takes effect upon particles of slurry already partly dehydrated, heat consumption thereby being reduced.

The invention is equally applicable to kilns provided with long or short chains suspended in such manner as to leave a free space for the passage of jets of slurry towards the deflectors. It is preferable to employ chains suspended from one extremity, and to form them, both at the entrance and the exit of the drying zone, of a length greater than the radius of the kiln and of a shorter length intermediately of the drying zone. In this case the rows of deflectors are disposed on the inner walls of the kiln and the slurry is injected at the lower part thereof. The long chains prevent the rebounding slurry from leaving the drying zone, while the shorter chains are not struck until after the particles of slurry have traversed a relatively long upward trajectory.

The invention will be described hereinafter with reference to the accompanying drawing in which it is illustrated and in which

Fig. 1 is a diagrammatic vertical cross section 5 of a rotary kiln according to the invention.

Fig. 2 illustrates diagrammatically part of the inner wall of a kiln with deflective surfaces of increasing width placed at equal distances.

Fig. 3 is a like view of the inner wall of a 10 kiln with deflective surfaces of equal width but placed at varying distances.

Fig. 4 is a cross section on line I—I of Fig. 1.

Fig. 5 is a view of the forward end of the kiln.

As shown in the drawing, 1 is the wall of the 15 rotary kiln, lined interiorly with insulating layer 1' which in turn is forced with a metallic plate doubling 1''. Long chains 2 are fitted at the forward end of kiln in such manner that the jets of slurry 6 projected by nozzles 3 have a clear 20 passage below these chains. In order to obtain an economical exchange of heat over the remaining part of the drying area, a desired number of short chains are fitted in such manner as to catch these splashing and rebounding particles of slurry which are still insufficiently dehydrated. Rows 7 of long chains define the 25 limits of the heating area. 5; 5a—5e and 5', 5a' . . . 5e' indicate the deflecting surfaces fixed to the inner wall of the kiln on to which the jets of slurry are projected and from which they rebound.

These sets of deflecting surfaces are offset relatively to each other. The deflecting surfaces themselves are inclined and may be fitted with 35 such inclination to the direction of jet or jets and may be so shaped that the jets of slurry will be scattered in a more or less horizontal or vertical direction as desired, in order to ensure a proportional distribution of slurry at all points of 40 the heating area.

With the purpose of distributing the slurry in quantities substantially commensurate with the temperature prevailing at each point in the heating area, the equidistant deflecting surfaces increase in width towards the inlet of gases, whose 45 direction of flow is indicated by arrow 8 (Fig. 2), or else when said deflecting surfaces are of same width, the clearance between two surfaces of the same set decreases. In this way more slurry is 50 dispensed at the point of gas inlet, where a higher temperature prevails than adjacent the gas outlet, thereby ensuring uniform drying of any material treated.

I claim:

55 1. In a process of feeding and distributing slurry to be burned in a rotary kiln by wet process having a drying area, blowing hot gases through said drying area towards the feeding end thereof, injecting said slurry into said area in a direction substantially parallel with the longitudinal axis of said area and against the direction of flow of said hot gases and projecting indirectly said slurry on the wall of kiln.

60 2. In a process of feeding and distributing slurry in a rotary kiln by wet process having a

drying area and chains arranged in said area, blowing hot gases through said area towards the feeding end thereof, injecting said slurry into said area in a direction substantially parallel with the longitudinal axis of said area and against the direction of flow of said hot gases and projecting indirectly said slurry on said chains.

65 3. In a rotary kiln heated by an inflow of hot gases, a drying area for the treatment of slurry, means for injecting said slurry against the direction of flow of said hot gases and deflecting surfaces fixed on the inner wall of kiln so as to deviate the jet of slurry on said wall of kiln.

70 4. In a rotary kiln heated by an inflow of hot gases, a drying area for the heat treatment of slurry, means for injecting said slurry against the direction of flow of said hot gases, chains arranged in said area and deflecting surfaces fixed on the inner wall of kiln so as to deviate 95 the jet of slurry on said chains.

75 5. In a rotary kiln heated by an inflow of hot gases, a drying area for the heat treatment of slurry, means for injecting said slurry against the direction of flow of said hot gases, deflecting 100 surfaces fixed on the inner wall of kiln, the width of said deflecting surfaces increasing in the direction of inlet end of said hot gases in the kiln.

80 6. In a rotary kiln heated by an inflow of hot gases, a drying area for the heat treatment of slurry, means for injecting said slurry against the direction of flow of said hot gases, deflecting 105 surfaces fixed on the inner wall of the kiln, said deflecting surfaces being of equal width and placed with decreasing intervals in the direction 110 of inlet end of said hot gases.

85 7. In a rotary kiln heated by an inflow of hot gases, a drying area for the heat treatment of slurry, means for injecting said slurry against the direction of flow of said hot gases, deflecting 115 surfaces fixed on the inner wall of the kiln, said deflecting surfaces being arranged in several sets offset relatively to each other.

90 8. In a rotary kiln heated by an inflow of hot gases, a drying area for the heat treatment of slurry, means for injecting said slurry against the direction of flow of said hot gases, deflecting 120 surfaces fixed on the inner wall of the kiln and arranged in several sets offset relatively to each other, said deflecting surfaces being shaped so 125 that the rebounding particles of slurry are directed in any given direction.

95 9. In a rotary kiln heated by an inflow of hot gases, a drying area for the treatment of slurry, means for injecting said slurry against the direction of flow of said hot gases, chains suspended in said area, deflecting surfaces fixed on the inner wall of the kiln so as to deviate the jet of slurry on said chains, said chains in the part 130 intermediate the drying area above the said deflective surfaces being of shorter length than those suspended at the hot gases' inlet and outlet ends.

ADOLPHE BUSCH.
